GYRATORY CRUSHER

George D. Becker, Wauwatosa, Wis., assignor to
Allis-Chalmers Manufacturing Company, Milwaukee, Wis., a corporation of Delaware

Application November 26, 1948, Serial No. 62,071

6 Claims. (Cl. 241—211)

1

This invention relates to gyratory crushers, and more specifically to gyratory crushers embodying fluid supporting means for the inner crushing member. The principal object of the invention is the provision of new and improved crushers of this type. A more specific object is to prevent damage to the crusher due to abnormal conditions of operation.

Another more specific object of the invention is the prevention of shock caused by upward "jumping" of the inner crushing element under certain conditions of operation.

It has been found that especially in primary gyratory crushers, if a peculiarly shaped stone is in the crushing chamber, the gyratory crushing action may force the head or inner crushing member to rise rather than crush the stone. This appears to be due to the relationship between the included angle of the crusher head and the included angle of the crusher chamber. A specific instance would be, for example, if the included angle of the head is 20° and the included angle in the crushing chamber is 28°. This instance is given merely by way of example and not by way of limitation. After the crusher head has risen, it and the shaft on which it is mounted drop, the lower end of the shaft striking its step bearing with great force. Accordingly, it is an object of the invention to provide means for obviating this undesirable result.

Other objects will appear hereinafter as the description of the invention proceeds.

The novel features of the invention and how the objects are attained will appear from this specification and the accompanying drawing showing several embodiments of the invention and forming a part of this application, and all of these novel features are intended to be pointed out in the claims.

In the drawing:

Fig. 1 is a central vertical section through a gyratory crusher embodying the invention; and

Fig. 2 is a sectional view of another embodiment of a detail of Fig. 1.

The gyratory crusher comprises a pair of relatively movable inner and outer crushing members 2 and 3 respectively, disposed in predetermined spaced cooperating crushing relationship to form an annular crushing chamber 4 located in a top shell 10; a main shaft 5 rigidly attached to the inner crusher member 2; a rotary eccentric 6 cooperating with the lower end of the main shaft 5 to produce gyration of the inner member 2 relative to the outer member 3; a drive sheave 7 adapted to be driven by a driving means (not

shown), for rotating the eccentric 6 by means of a pinion shaft 8 driving the eccentric through a bevel gear 9, and a suitable supporting shell 12 for supporting the crusher structure.

5 The upper end of the main shaft 5 is fulcrumed in spider arms 11, that are supported by means of the top shell 10 which also provides a fixed support for the outer crushing member 3. The eccentric 6 is rotatably located in the supporting shell 12, and rests upon an eccentric wearing plate 14 which in turn is supported by a bottom plate 13.

15 The lower end of the main shaft 5 is here shown as resting directly on displaceable structure here shown as washers 17, 18 and a piston 15. The intermediate washer 17 is carried by the washer 18 which is supported by the piston 15 having a cup shaped section located in its upper face to receive a complementary portion 20 of the washer 18. The displaceable piston 15 defines with the bottom plate 13 an expandable chamber 16 which is filled with fluid. The fluid in chamber 16 supports and axially positions the inner crushing member 2. The fluid may be oil or other suitable liquid. The piston 15 is vertically movable within a cylindrical opening (here shown as lined) in the bottom plate 13, and which may be provided with a vertical longitudinal recess 19 to receive a key 20 to prevent turning caused by the gyratory motion of the inner crusher member 2. A washer clamp plate 21 is placed in abutting relationship with and if desired, secured to the lower face of the piston 15 and fitted with packing 22 to seal the fluid 30 in its confined working area.

35 Fluid supply means, here shown as an accumulator 24, is hydraulically connected to the chamber 16. Operable within the chamber 24 is a displaceable element comprising a lower piston 40 25 and an upper piston 26. A primary conduit 31 extends liquid from the chamber 16 through a conduit 32, a flow regulator 34, and a conduit 31 into direct contact with the lower face of the lower piston 25 to bias the coating upper piston 26, under normal crushing conditions, to a limited position against a stop shown in Fig. 1 as a flange 28. The lower piston 25 may be provided with an annular sealer ring 27. Defined by the lower and upper pistons 25 and 26, there is here shown 45 a relatively small space 29 permitting compression of the ring 27. Biasing means, shown in Fig. 1 as an elastic fluid confining chamber 23, is provided to maintain a desired pressure on the upper face of piston 26. Means for admitting compressed air, nitrogen or other suitable elastic

fluid into the elastic fluid chamber 23 to thereby continuously maintain the desired pressure within the elastic fluid chamber, is provided for as indicated at 30.

A substitute for the elastic fluid chamber 23 is illustrated in Fig. 2. This alternative embodiment comprises a cylinder 52 having an internal laterally extending flange 53 at its lowermost end, to function as a stop means for the upward displacement of the displaceable element 25, 26. An actuating member 54 is biased against the upper piston 26 by a resilient means such as a compressed coil spring 55 reacting between a spring seat 56 (which may be made integral with the actuating member 54) and a cylinder head 57 that is secured to the cylinder 52 by means of bolts 58. The actuating member 54 may at its lower end be functionally integral with the piston 26, or, as here shown, abutted by said piston. Hence the piston 26 is adapted to push the member 54 upwardly against the bias of spring 55, and the spring 55 is adapted to cause the member 54 to force the piston downwardly.

The displaceable element 25, 26 may function to cooperate with a flow regulator 34 which is connected at its upper end to the liquid accumulator chamber 24 by means of a conduit 33, and at its lower end with the primary conduit 31 by means of a conduit 32. Disposed within the flow regulator housing 35 are flow controlling valves comprising a resiliently biased valve body 36 and return flow throttling means shown as a needle valve body 38. The valve body 36 is biased against the discharge end of a passage 39 by means of a spring 37, thereby, in that position, preventing flow therethrough. Upon release of pressure on the liquid in chamber 16 due to the upward movement of the inner crusher member 2, and hence on the extended liquid in an intermediate passage 40 and the liquid in the accumulator chamber 24, the compressed elastic fluid in elastic fluid chamber 23 will expand, thereby forcing pistons 25, 26 downward resulting in the compression of spring 37 to effect the opening of the discharge end of passage 39 to permit the liquid or a portion of the liquid in the liquid accumulator chamber 24 to discharge into the intermediate passage 40 to thereby increase the volume of liquid in the expansible chamber 16 at a comparatively rapid rate. When the pressure upon the liquid in chamber 16 is resumed, the liquid in the intermediate passage 40 and the spring 37 will move the valve body 36 against the discharge end of the passage 39 to prevent liquid from flowing through it into the liquid accumulator chamber 24. Readmission of the volume of liquid discharged from the liquid accumulator chamber 24 is provided for through means of a passage 41 and an orifice 42. The increased volume of liquid in the expansible chamber 16 or the volume of liquid discharged from the liquid accumulator chamber 24 is readmitted to the liquid accumulator chamber 24 at a relatively slow rate, predetermined by the downward pressure exerted by the inner member 2, the opposing pressure of the elastic fluid in the elastic fluid chamber 24 (or the opposing pressure of the spring 55), and the opening through the orifice 42 as determined by the setting of the needle valve body 38.

The flow regulating means 34 may also be entirely omitted. With this omission, the increased volume of liquid in chamber 16 will be readmitted into the accumulator chamber 24 at a rate predetermined by the downward pressure

exerted by the inner member 2 and commensurate to the requisite force required to recompress the elastic fluid in chamber 23, or to recompress the spring 55.

Connected with the primary conduit 31 is a conduit 43 for extending the liquid in the chamber 16 into an overload accumulator chamber 44 under certain conditions. Upon abnormal increases in pressure upon the liquid in the chamber 16, the liquid extended from the chamber will be forced into the overload accumulator chamber 44 to thereby provide for the absorption cushioning of abnormally high crushing pressures. The specific construction of the overload accumulator 44 is not a part of the present invention. Any construction which will permit liquid to enter the chamber 44 when the liquid pressure exceeds a predetermined value and which expels the liquid upon reduction in pressure to said predetermined value is satisfactory.

A relief valve 45 is also provided for in the conduit 43 to release pressures in the chamber 16 that exceed substantially the pressures that could be absorbed by the overload accumulator chamber 44.

Connected to the conduit 43 is a filler pipe 46 communicating chamber 16 with a liquid reservoir 47. A hand pump 48 is provided for in the filler pipe 46 for adjusting the spaced relationship of the cooperating crushing members 2, 3 to vary the size of the discharge opening associated with the crushing chamber 4, by varying the quantity of liquid in the chamber 16. By turning the pump handle 49 in a given direction the liquid in the chamber 16 will be increased, thereby effecting a rise of the inner crusher member 2 to decrease the size of the discharge opening. If it is desired to increase the size of the discharge opening, liquid from the chamber 16 is pumped into the reservoir 47 by turning the pump handle 49 in the opposite direction. A petcock 50 may be disposed in filler pipe 46 to remove all air from direct contact with the liquid in chamber 16, to insure constant standards of performance.

A valve 51 of any suitable form is also located in filler pipe 46. This valve may be manually adjusted to effect the locking of the liquid in the system when in closed position, thereby preventing a reverse flow of liquid to the reservoir 47 through the pump 48. If it is desired to vary the discharge opening of the crushing chamber 4, the valve 51 must be positioned to permit free flow of liquid between the chamber 16 and the pump 48.

Under normal crushing conditions, a predetermined pressure is established in the chamber 16, sufficient to cause the displaceable structure, washers 17, 18 and piston 15, to support the shaft assembly, that is, the shaft 5 and the head 2. This pressure, as aforesaid, is substantially less than the abnormal pressure required to effect the cushioning function of the overload accumulator chamber 44.

If a peculiarly shaped piece of material is admitted to or formed in the crushing chamber 4 between the members 2 and 3, the inner crusher member 2 will suddenly be displaced in an upward direction. This upward displacement will release substantially all the pressure on the liquid in chamber 16. The pressure release will be transmitted to the displaceable element 25, 26 in liquid accumulator chamber 24.

permitting expansion of the compressed elastic fluid in elastic fluid chamber 23 into the accumulator chamber 24 by forcing the displaceable element 25, 26 in a downward direction. It will be evident that if the embodiment of Fig. 2 is used, the beforementioned pressure release will permit the expansion of spring 55, thereby forcing the displaceable element 25, 26 downward. The spring biased valve body 36 will assume an open position in response to the downward displacement of the displaceable element 25, 26 to provide a rapid increase in quantity of liquid in the chamber 16 to effect upward displacement of the piston 15 concurrent with the sudden upward displacement of the inner crusher member 2, thereby minimizing, preferably to the extent of elimination, any gapping or relative vertical motion between the step support piston 15 and the lower end of shaft 5. Upon the termination of the upward displacement and the commencement of the downward movement of inner member 2, the piston 15 in response thereto is pushed downwardly by the weight of the shaft assembly at a predetermined relatively slow rate, due to the relatively slow decrease in quantity of liquid in the chamber 16. The passage of liquid from the chamber 16 to the liquid accumulator chamber 24 is restricted to relatively slow flowage due to the then closed position the valve body 36, and the small opening through orifice 42. Normal crushing conditions are again resumed when the displaceable element 25, 26 has reached the limit of its upward travel, against the flange 28. It is readily seen that the piston 15 and hence the crusher head 2, will then be in its initial position.

It will also be evident that if the flow regulating means 34 is omitted, readmission of liquid to the chamber 24 will nevertheless be retarded due to the resistance to compression of the fluid in chamber 23 (or the resistance to compression of the spring 55).

If an abnormally hard piece of material such as a piece of steel is admitted to the crushing chamber 4 between members 2 and 3, the pressure upon the piston 15 becomes relatively high thereby subjecting the body of liquid in the chamber 16 to a corresponding increase in pressure which is transmitted through the conduits 31 and 43 to the overload accumulator chamber 44. If the relatively high pressure becomes sufficient, it will be absorbed by the overload accumulator to thereby prevent injurious shock. If the excessive pressure is relieved, the liquid absorbed by the overload accumulator chamber 44 will be discharged to the chamber 16 to again permit normal crushing conditions.

As an example of the relative pressures that may exist, we may consider a case in which the shaft assembly weighs about 50,000 pounds. With a piston 15 of suitable area, the static pressure in the chamber 16 may be about 115 p. s. i. and the working pressure of the order of 350 p. s. i. or more. Either the static or working pressure will of course exist in the conduits 31, 32, 33, 43, and 46. The normal pressure of the elastic fluid in chamber 23 (or the normal compression of spring 55) may be of the order of 50 p. s. i. which is less than the static pressure and much less than the working pressure but sufficient to keep the piston 15 against the step bearing. The abnormal pressure required to bring into function the coating overload accumulator chamber is far in excess of the normal working pressure, for example 600 p. s. i.

From the foregoing it will be apparent to those skilled in the art that the illustrated embodiment of the invention provides new and improved gyratory crushers and accordingly accomplishes the objects of the invention. On the other hand, it will also be obvious to those skilled in the art that the illustrated embodiment of the invention may be variously changed and modified, or features thereof, singly or collectively, embodied in other combinations than that illustrated, without departing from the spirit of the invention, or sacrificing all of the advantages thereof, and that accordingly the disclosure herein is illustrative only, and the invention is not limited thereto.

It is claimed and desired to secure by Letters Patent:

1. A gyratory crusher comprising longitudinally extending inner and outer crushing members, means for gyrating said inner crushing member relative to said outer crushing member, means supporting said inner crushing member for axial movement relative to said outer crushing member and for gyratory movement about said axis relative to said outer crushing member, said supporting means including an expansible fluid chamber operable to move and position said inner crushing member relative to said outer crushing member, said chamber being filled with fluid of a predetermined quantity and pressure sufficient to support said inner crushing member in a predetermined axial position relative to said outer crushing member, fluid supply means hydraulically connected with said chamber biased under pressure less than said predetermined pressure to operate in response to an expansion of said fluid chamber occasioned by the movement of said inner crushing member axially in a direction away from said chamber to supply fluid to maintain said chamber filled with fluid at a pressure insufficient to support said inner crushing member but sufficient to retard movement of said inner crushing member back to said predetermined axial position, and said fluid supply means vice versa operable to receive fluid from said chamber in response to the contraction of said chamber upon the return of said inner crushing member to said predetermined axial position so that said inner crushing member is gradually returned to said predetermined position.

2. A gyratory crusher comprising longitudinally extending inner and outer crushing members, means for gyrating said inner crushing member relative to said outer crushing member, means supporting said inner crushing member for axial movement relative to said outer crushing member and for gyratory movement about said axis relative to said outer crushing member, said supporting means including an expansible fluid chamber defined in part by displaceable structure for supporting and moving said inner crushing member axially relative to said outer crushing member, said chamber being filled with fluid under a predetermined pressure to position said displaceable structure and said inner crushing member supported thereon at a predetermined axial position relative to said outer crushing member, an accumulator filled with fluid under said predetermined pressure and communicating with said fluid in said chamber, a piston slidably mounted in said accumulator having one face exposed to said predetermined pressure of said fluid, means opposing said predetermined fluid pressure on said piston comprising biasing means continually

applying a pressure less than said predetermined pressure to the other face of said piston to cause said piston to move in the other direction to operate said accumulator to urge said fluid to flow into said chamber at said reduced pressure and expand said chamber in response to axial movement of said inner crushing member in a direction away from said chamber, said reduced fluid pressure being insufficient to support said inner crushing member at said predetermined axial position but sufficient to maintain said chamber filled with fluid and to expand said chamber to urge the continued engagement of said displaceable structure with said inner crushing member, and said accumulator vice versa operable to receive fluid from said chamber in response to the contraction of said chamber upon the return of said inner crushing member to said predetermined axial position so that said inner crushing member is gradually returned to said predetermined position.

3. A gyratory crusher comprising longitudinally extending inner and outer crushing members, means for gyrating said inner crushing member relative to said outer crushing member, means supporting said inner crushing member for axial movement relative to said outer crushing member and for gyratory movement about said axis relative to said outer crushing member, said supporting means including an expansible fluid chamber defined in part by displaceable structure for supporting and moving said inner crushing member axially relative to said outer crushing member, said chamber being filled with fluid under a predetermined pressure to position said displaceable structure and said inner crushing member supported thereon to a predetermined axial position relative to said outer crushing member, an accumulator filled with fluid under said predetermined pressure communicating with said fluid in said chamber, a piston slidably mounted in said accumulator having one face exposed to said predetermined pressure of said fluid, means opposing said predetermined fluid pressure on said piston comprising a stop to prevent movement of said piston in one direction to maintain said chamber filled with fluid at said predetermined fluid pressure for supporting said inner crushing member on said displaceable structure at said predetermined axial position, and biasing means continually applying a pressure less than said predetermined pressure to the other face of said piston to cause said piston to move in the other direction away from said stop to operate said accumulator to urge said fluid to flow into and fill said chamber at said reduced pressure, expand said chamber in response to axial movement of said inner crushing member in a direction away from said chamber, said reduced fluid pressure being insufficient to support said inner crushing member at said predetermined axial position but sufficient to maintain said chamber filled with fluid and to expand said chamber to urge the continued engagement of said displaceable structure with said inner crushing member, and said accumulator vice versa operable to receive fluid from said chamber in response to the contraction of said chamber upon the return of said inner crushing member to said predetermined axial position so that said inner crushing member is gradually returned to said predetermined position.

4. A gyratory crusher comprising longitudinally extending inner and outer crushing members, means for gyrating said inner crushing

member relative to said outer crushing member, means supporting said inner crushing member for axial movement relative to said outer crushing member and for gyratory movement about said axis relative to said outer crushing member, said supporting means including an expansible fluid chamber filled with fluid and operable to move and position said inner crushing member relative to said outer crushing member, said chamber being filled with fluid of a predetermined quantity and pressure sufficient to support said inner crushing member in a predetermined axial position relative to said outer crushing member, fluid supply means hydraulically connected with said chamber biased under pressure less than said predetermined pressure to operate in response to an expansion of said fluid chamber occasioned by the movement of said inner crushing member axially in a direction away from said chamber to supply fluid to maintain said chamber filled with fluid at a reduced pressure insufficient to support said inner crushing member at said predetermined axial position, and flow regulating means interposed between said fluid supply means and said chamber operable to open in response to said chamber expansion to permit the free flow of said fluid from said fluid supply means to said chamber and vice versa operable to close when the fluid pressure in said fluid chamber exceeds the fluid pressure in said fluid supply means, said flow regulating means including a throttling means to restrict the passage of fluid from said chamber to said fluid supply means in response to the contraction of said chamber upon the return of said inner crushing member to said predetermined axial position, so that said inner crushing member is gradually returned to said predetermined position.

5. A gyratory crusher comprising longitudinally extending inner and outer crushing members, means for gyrating said inner crushing member relative to said outer crushing member, means supporting said inner crushing member for axial movement relative to said outer crushing member and for gyratory movement about said axis relative to said outer crushing member, said supporting means including an expansible fluid chamber defined in part by displaceable structure for supporting and moving said inner crushing member axially relative to said outer crushing member, said chamber being filled with fluid under a predetermined pressure to position said displaceable structure and said inner crushing member supported thereon at a predetermined axial position relative to said outer crushing member, an accumulator filled with fluid under said predetermined pressure and communicating with said fluid in said chamber, a piston slidably mounted in said accumulator having one face exposed to said predetermined pressure of said fluid, means opposing said predetermined fluid pressure on said piston comprising biasing means continually applying a pressure less than said predetermined pressure to the other face of said piston to cause said piston to move in the other direction to operate said accumulator to urge said fluid to flow into said chamber at said reduced pressure and expand said chamber in response to axial movement of said inner crushing member in a direction away from said chamber, said reduced fluid pressure being insufficient to support said inner crushing member at said predetermined axial position but sufficient to maintain said chamber filled with fluid and expand

75

said chamber to urge the continued engagement of said displaceable structure with said inner crushing member, and flow regulating means interposed between said accumulator and said chamber operable to open in response to said chamber expansion to pass fluid freely from said accumulator to said chamber and vice versa, operable to close when the fluid pressure in said chamber exceeds the fluid pressure in said accumulator, said flow regulating means including throttling means to restrict the passage of fluid from said chamber to said accumulator in response to the contraction of said chamber upon the return of said inner crushing member to said predetermined axial position so that said inner crushing member is gradually returned to said predetermined position.

6. A gyratory crusher comprising longitudinally extending inner and outer crushing members, means for gyrating said inner crushing member relative to said outer crushing member, means supporting said inner crushing member for axial movement relative to said outer crushing member and for gyratory movement about said axis relative to said outer crushing member, said supporting means including an expansible fluid chamber defined in part by displaceable structure for supporting and moving said inner crushing member axially relative to said outer crushing member, said chamber being filled with fluid under a predetermined pressure to position said displaceable structure and said inner crushing member supported thereon at a predetermined axial position relative to said outer crushing member, an accumulator filled with fluid under said predetermined pressure communicating with said fluid in said chamber, a piston slidably mounted in said accumulator having one face exposed to said predetermined pressure of said fluid, means opposing said predetermined fluid pressure on said piston comprising a stop to prevent movement of said piston in one direction to maintain said chamber filled with fluid at said predetermined fluid pressure for supporting said

inner crushing member at said predetermined axial position, and biasing means continually applying a pressure less than said predetermined pressure to the other face of said piston to cause said piston to move in the other direction away from said stop to operate said accumulator to urge said fluid to flow into said chamber at said reduced pressure and expand said chamber in response to axial movement of said inner crushing member in a direction away from said chamber, said reduced fluid pressure being insufficient to support said inner crushing member at said predetermined axial position but sufficient to maintain said chamber filled with fluid and expand said chamber to urge the continued engagement of said displaceable structure with said inner crushing member, and flow regulating means interposed between said accumulator and said chamber operable to open in response to said chamber expansion to pass fluid freely from said accumulator to said chamber and vice versa operable to close when the fluid pressure in said chamber exceeds the fluid pressure in said accumulator, said flow regulating means including throttling means to restrict the passage of fluid from said chamber to said accumulator in response to the contraction of said chamber upon the return of said inner crushing member to said predetermined axial position so that said inner crushing member is gradually returned to said predetermined position.
